GEAR AND CLUTCH MECHANISM FOR SPINNER TYPE CLOTHES-WASHING MACHINES

Carl S. Dayton, Bridgeport, Conn., assignor to
General Electric Company, a corporation of
New York

Application November 20, 1947, Serial No. 787,228

4 Claims. (Cl. 193—3.5)

1

The present invention relates to clothes washing machines of the type wherein washing is performed in a basket by an agitator, the basket afterwards being rotated to centrifugally extract the water from the clothes.

The object of the invention is to provide an improved construction and arrangement in a washing machine of this type which is simple in structure, reliable in operation and capable of being manufactured at low cost. The invention is especially well adapted for small portable machines adapted to be readily lifted manually and placed on a drain board, for example, when the machine is being used. However, the invention is not limited thereto necessarily.

For a consideration of what I believe to be novel and my invention, attention is directed to the following specification and to the claims appended thereto.

In the drawing, Fig. 1 is a sectional view of a washing machine embodying my invention; Fig. 2 is a sectional view on a larger scale of the operating mechanism, the section of certain parts being on the irregular section, line 2—2, Fig. 4; Fig. 3 is a detail view taken on line 3—3, Fig. 2; Fig. 4 is a detail view taken on line 4—4, Fig. 2; Fig. 5 is a detail view taken on line 5—5, Fig. 2 and Fig. 6 is a sectional view of the upper end of the agitator showing parts in a position different from that of Fig. 2.

Referring to the drawing, 1 indicates the tub of the washing machine which may be supported on a base 2 provided with feet or casters 3. In the tub is a unitary structure comprising a spin basket 4 in which the clothes are washed, an agitator 5 for performing the washing operation, and a sealed casing 6 in which is an electric motor and mechanism operated by it for oscillating the agitator to perform the washing operation, the basket being then stationary, and for spinning the basket and the agitator to extract the water from the clothes. This unitary structure may be supported in the tub in any suitable way, the specific supporting means forming no part of my present invention. In the present instance, it is shown as being supported by a base spring 7 and three side springs 8. Base spring 7 is positioned between a strap 9 fixed to the bottom 10 of tub 1 and the bottom of casing 6. The lower end of casing 6 projects through an opening 11 in bottom wall 10. The space between the edge of opening 11 and casing 6 is sealed by a suitable flexible diaphragm 12 attached at one edge to the wall surrounding opening 11 and at the other edge to casing 6.

2

Springs 8 are tension springs and are connected at one end to ears 13 on casing 6 and at the other ends to ears 14 fixed to the inner surface of the side wall of tub 1. This arrangement serves to provide a yielding resilient mounting for the unitary structure comprising casing 6, the mechanism therein, the basket 4, and the agitator 5. Tub 1 has an open top closed by a suitable cover 15 and handles 16 on its sides by which it may be lifted.

Casing 6 is shown as being formed in two sections, an upper section 17 and a lower section 18. The sections are provided with meeting flanges 19 which may be clamped together in 15 sealing relation by studs 20. The motor for operating the mechanism is located in lower casing section 18. It comprises a suitable field structure 20a carried by casing section 18 and an armature 21 fixed on a shaft 22. Shaft 22 is supported in an upper bearing 23 carried by a diaphragm 24 which, at its edges, is supported on a shoulder 25 in casing section 18, and by a bearing in lower section 18 which may be in the form of a suitable step bearing (not shown). Casing 6 is suitably sealed to make it liquid tight to prevent leakage either to or from the casing.

On the upper end of motor shaft 22 is a pinion 26 which may be formed integral with the shaft and which meshes with a gear wheel 27 mounted 30 on a shaft 28 which in turn is carried by upper and lower walls 29 and 30 of a gear frame 31. Formed integral with gear wheel 27 is an eccentric 32 surrounding which is an eccentric strap 33 provided with an arm 34 which in turn is connected to an arm 35 fixed to a hub 36. Hub 36 is supported on the upper end of pinion 26 which forms a step bearing for it. It is connected to the lower end of a vertical agitator shaft 37. Shaft 37 is journaled in lower and upper bearings 38 and 39 at the lower and upper ends of a vertical tubular spin shaft 40. The lower end of spin shaft 40 is fixed in a collar 41 by a pin 41a or other suitable means. Collar 41 forms a part of gear frame 31. Spin shaft 40 is journaled in a bearing 42 carried in the top wall of casing section 17. At 42a is a bearing pressed into an opening in lower wall 30 in which motor shaft 22 is positioned. Motor shaft 22 has a deep socket 43 in which is located an extension 44 which 45 forms the lower end of shaft 37. Between the lower end of shaft extension 44 and the bottom of socket 43 is a coiled compression spring 45 which biases shaft 37 in an upward direction.

Spin basket 4 is fixed to tubular spin shaft 40. In the present instance the bottom wall of the

basket is shown as having a conical upwardly projecting portion 46 which terminates in a sleeve 47 surrounding shaft 40. At its lower end sleeve 47 has a flat surface which rests on a collar sleeve 48 keyed to shaft 40. Collar 48 is fastened to sleeve 47 by a pin 49 thus connecting the basket to spin shaft 40.

Agitator 5 is of known construction comprising a tubular center post 50 and blades 51. It is fixed to turn with shaft 37 by means of a non-circular opening at the upper end of post 50 which fits over a non-circular tapered nut 52 fastened on the upper end of shaft 37 and is held on the shaft by a knurled nut 52a which threads onto the upper end of the shaft. At its lower end, post 50 is journaled on a bearing 53 pressed on sleeve 47.

During washing, gear frame 31 is stationary and the motor oscillates the agitator through pinion 26, gear wheel 27, the eccentric connection and shaft 37. During spinning of the basket the motor is connected directly to gear frame 31 to rotate the gear frame, the tubular shaft 40 and the spin basket, shaft 37 and the agitator 5 being rotated along with the basket.

One feature of my invention is the mechanism for connecting the motor shaft directly to gear frame 31 for spinning the basket. Fixed to the underside of gear frame 31 is a depending clutch ring 55 adapted to be engaged by suitable clutch facings 56 on the outer ends of a pair of clutch arms 57. The clutch arms are pivotally mounted on pins 58 carried by opposed ears which project from a collar 59 fixed to motor shaft 22 by suitable means such as the pin 60. The inner ends of clutch arms 57 stand adjacent to collar 59 on opposite sides of the collar and in collar 59 and shaft 22 are holes in which are located sliding pins 61. The inner ends of pins 61 terminate in shaft socket 43 and normally engage the surface of shaft extension 44 as shown in Figs. 2 and 4. In this position, the outer ends of the pins engage the inner ends of clutch arms 57, as shown in full lines in Fig. 4 to hold positively clutch facings 56 out of engagement with clutch ring 55. In the lower end of shaft extension 44 is an annular groove 62. When the motor shaft is to be connected to gear frame 31, shaft 37 and the agitator along therewith is lifted to bring groove 62 into line with the inner ends of pins 61 whereby when the motor rotates the outer ends of arms 57, being no longer held by pins 61, are thrown out by centrifugal force to bring the clutch facings 56 into engagement with clutch ring 55, whereby the motor armature is connected directly to gear frame 31 by the centrifugal clutch. At this time pins 61 move radially inwardly, their inner ends moving into groove 62.

Shaft 37 has two positions with respect to shaft 40, a lower or agitate position as shown in Fig. 2, wherein pins 61 lock centrifugal clutch arms 57 against movement, and an upper or spin position wherein groove 62 is in line with the ends of pins 61 to release the clutch arms. To lock shaft 37 in these two positions, I provide a detent mechanism comprising a socket 63 in the upper end of shaft 37 in which is positioned a shift pin 64 biased upward by a spring 65, upward movement being limited by a stop pin 66 driven across shaft 37 which extends through a vertical slot 67 in shift pin 64. In the wall of socket 63 are several circumferentially spaced holes in which are detent balls 68 adapted to engage in annular detent grooves 69 and 70 in the inner surface of bearing 39. In shift pin 64 is an annular groove

71 having beveled ends, the groove being normally positioned above balls 68. Shift pin 64 holds the balls in either groove 69 or groove 70 to lock shaft 37 against vertical movement. In Fig. 2 shaft 37 is shown as being locked in its lower or agitate position, balls 68 projecting partly into groove 69 and being so held by the outer surface of shift pin 64. To move the shaft to spin position, shift pin 64 is pressed down to bring groove 71 into line with balls 68 to release them, whereupon shaft 37 may be moved up to spin position. The balls are carried along with shaft 37 and as soon as they come into line with the other groove 70, spring 65 will move shift pin 64 (pressure on it having been removed) back to its normal position to force the balls into such other groove to lock the shaft in its spin position as shown in Fig. 6. The beveled end of groove 71 serves to cam the balls outward. In similar manner shaft 37 may be moved back to agitate position. This detent construction has the advantage that it is positive in action, and no amount of end thrust will cam the balls out of groove 69 or 70 because their movement is blocked by the shift pin. By the use of balls I avoid any interference with the relative rotation of shafts 37 and 40. Shaft 37 can be moved only when shift pin 64 is pressed down. The upper end of groove 62 is beveled to act as a cam for forcing pins 61 outward when shaft 37 is moved down from spin to agitate position.

It is desirable (although not necessary) during an agitate cycle to lock gear frame 31 against turning movement. In so far as my present invention is concerned, any suitable means may be used for this purpose. In the present instance, I have shown a means invented by John H. Palmer and which forms subject matter of his application Serial No. 737,114, now Patent No. 2,487,685, issued February 14, 1950, filed of even date herewith, and assigned to the same assignee as the instant application. Such locking means comprises a collar 72 on shaft 40 in which is a radial hole in which is positioned a releasing pin 73. Any suitable means may be provided for limiting radially outward movement of pin 73 under the action of centrifugal force. For example, it may be provided with a peened over inner end or a head as shown in Figs. 1 and 5. In collar 72 in line with the hole is a notch 74 with which engages the inner end of a locking pin 75. Pin 75 is positioned in a socket 76 in casing wall 17 and is biased to a position toward notch 74 by a spring 77. In shaft 37 is an annular groove 78 having beveled ends in which the inner end of pin 75 normally stands, thus permitting locking pin 75 to engage notch 74 to lock shaft 40 and gear frame 31, to which it is attached, against turning. This is its position during an agitate cycle. When shaft 37 is lifted to spin position to release the centrifugal clutch so that it may connect the motor to gear frame 31, releasing pin 73 is cammed outward by the lower beveled edge of groove 78 to move locking pin 75 out of notch 74, the releasing pin being moved to a position where it is just flush with the surface of collar 72. This releases shaft 40. When shaft 40 is turning, the inner end of pin 75 rides on the surface of collar 72.

If desired, the arrangement may be such that shaft 37 is disconnected from the gearing carried by frame 31 during the spin cycle. To this end shaft 37 is shown as being provided with a tapered non-circular clutch head 80 which fits in a socket 81 in a hub 38 so that when shaft 37 is raised to

spin position to release the centrifugal clutch locking mechanism, clutch head 80 is lifted free of socket 81, hub 36 being then free to oscillate on shaft 37. This arrangement is of advantage in that in shifting from agitate to spin it prevents any agitation of the shaft during the period required for the motor to reach a speed sufficiently high to effect actuation of clutch arms 57 to connect the motor shaft to frame 31. At 82 is a pipe which during operation of the machine directs oil to parts requiring lubrication.

While I have shown and described a particular embodiment of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. For use in a clothes washing machine or the like of the type disclosed, concentric agitator and spin shafts movable axially relative to each other, and means for actuating the agitator shaft or rotating the spin shaft comprising a casing into which ends of the shafts project, a gear cage rotatably mounted in the casing to which the spin shaft is connected, an electric motor, gearing carried by the cage which connects the motor to the agitator shaft, a clutch for connecting the motor to the gear cage, and means actuated by movement of said shafts axially relative to each other for rendering said clutch effective to connect the motor to the gear cage.

2. For use in a clothes washing machine or the like of the type disclosed, concentric agitator and spin shafts movable axially relative to each other, and means for actuating the agitator shaft or rotating the spin shaft comprising a rotatably mounted gear cage, a motor, gearing carried by the cage through which the motor actuates the agitator shaft, a normally open clutch, and means actuated by the movement of said shafts axially relative to each other for rendering said clutch effective to connect the motor to the gear cage and spin shaft for rotating the spin shaft.

3. For use in a clothes washing machine or the like of the type disclosed, mechanism comprising a tubular spin shaft, a rotatable gear cage to which it is connected, a motor, a clutch ring carried by the gear cage, pivoted clutch arms carried by the motor shaft movable by rotation of the motor shaft for connecting them to the clutch ring, an agitator shaft positioned inside said tubular shaft, gearing carried by the gear cage through which the motor shaft is connected to the agitator shaft, and means actuated by axial movement of the agitator shaft for holding said clutch arms against movement.

4. For use in a clothes washing machine or the like of the type disclosed, mechanism comprising a tubular spin shaft, a rotatable gear cage to which it is connected, a motor, a clutch ring carried by the gear cage, pivoted clutch arms carried by the motor shaft movably by rotation of the motor shaft for connecting them to the clutch ring, transversely movable pins positioned in openings in said tubular spin shaft, the outer ends of which are adapted to engage ends of said clutch arms to hold them out of clutching engagement with the clutch ring, an agitator shaft positioned inside said tubular shaft, gearing carried by the gear cage through which the motor shaft is connected to the agitator shaft, and means carried by the agitator shaft for holding said pins in engagement with the clutch arms to hold the clutch arms out of engagement with the clutch ring, said means being released by movement of the agitator shaft with respect to the spin shaft.
